UNITED STATES PATENT OFFICE.

JULIUS GROETSCHEL, OF VOGTLAND, GERMANY.

SHUTTLE EMBROIDERING-MACHINE.

1,112,131.

Specification of Letters Patent. Patented Sept. 29, 1914.

Application filed February 4, 1913. Serial No. 746,183.

To all whom it may concern:

Be it known that I, JULIUS GROETSCHEL, a subject of the German Emperor, residing at Plauen, in Vogtland, in the Kingdom of 5 Saxony, Germany, have invented certain new and useful Improvements in Shuttle Embroidering-Machines, of which the following is a specification:

The subject matter of my invention consists of a shuttle embroidering machine, which differs from similar machines already known in that two rows of shuttles are adapted to be displaced vertically upward and downward, so that the needles are able 15 alternately to coöperate either with the one or with the other row of shuttles.

In the accompanying drawing a constructional form of the invention is shown by way of example.

20 Figure 1 is a vertical cross-section through the frame of the machine, viewed from the left side. Fig. 2 is a small portion of Fig. 1 shown on a larger scale. Fig. 3 is a rear view.

25 As shuttle embroidering machines in all parts and in all their different mechanisms are already thoroughly well-known as regards their method of operation, the drawing in this case merely shows essentially 30 that which I consider to be my invention. In the drawing there are also shown some parts of the embroidery machine which are also already known, but this has been done merely with a view to assist in explaining 35 the co-relationship existing between them and the frame of the machine.

In the transverse wall (1) of the machine frame there are arranged, on the front side of the machine, the iron beams (2, 3), while 40 the iron beams (4, 5) are on the rear side of the machine. The parts (1) to (5) thus form the actual rigid vertical machine frame. The dotted line (x—x) is intended to represent the embroidery-work which, as 45 is well-known, is tightly stretched in a large square frame and, when it is desired to embroider further, it must be moved backward and forward in all directions in front of the needles (6, 7).

The novel feature which characterizes my 50 invention is based upon the fact that two rows of shuttles are adapted to be moved vertically, by means of the rod (10), upward and downward opposite the row of needles (6). As shown in Fig. 2 the shuttles (8 and 55 9) coöperate with the needles (6). In Fig. 1 the shuttles are shown in the elevated position, so that the row of shuttles (9) is opposite the row of needles (6). The same remarks apply in relation to the shuttles (8') 60 and (9'), which are intended to work alternately with the row of needles (7).

The shuttles move in the manner known along the shuttle races (11, 12) and are moved to and fro in a horizontal direction 65 by known actuating devices (13, 14). The shuttle races (11, 12) are fastened to the rod (10). This rod (10) is provided with teeth (15) which engage with the teeth of the wheel (16). When, by the exertion of any 70 force whatsoever, the shaft (17) is caused to rotate, then the rod (10) is caused to move vertically and then, whensoever it be necessary or when it be desirable, this movement 75 will be brought into play in such a way that first the row of shuttles (8), and then the other row of shuttles (9), will alternately be caused to take up such an altitude that they will coöperate, with the row of needles (6).

80 What I claim and desire to secure by Letters Patent, is:

1. In a shuttle embroidering machine a supporting frame, a rod mounted for vertical reciprocation in said frame, a plurality 85 of rows of shuttle raceways fixed on said rod, shuttles mounted in each raceway, a row of needles and means for shifting said raceways whereby, when one raceway is shifted into coöperative relation with said 90 row of needles another raceway is shifted into inoperative relation with said row of needles.

2. In a shuttle embroidering machine a supporting frame, rows of shuttles adapted 95 to reciprocate vertically arranged in said frame, a rod to reciprocate said rows of shuttles, and a fixed row of needles opposite

to which the rows of shuttles alternately appear for coöperation therewith.

3. In a shuttle embroidering machine, a supporting frame, a shuttle race thereon means to move the shuttles horizontally in said race, a toothed rod secured to the shuttle races, a rotating toothed wheel engaging with said toothed rod and a row of needles

opposite to which said rows of shuttles are alternately moved by said rod, as specified. 10

In testimony whereof I affix my signature in presence of two witnesses.

JULIUS GROETSCHEL.
